[57] CLAIM

The ornamental design for an eyeglass front, as shown and
described.

DESCRIPTION

FIG. 1 is a perspective view of an eyeglass front showing my
new design;

FIG. 2 is a front elevational view thereof;

FIG. 3 is a rear elevational view thereof;

FIG. 4 is a left side elevational view thereof, the side
opposite being a mirror image;

FIG. 5 is a top plan view thereof;

FIG. 6 is a bottom plan view thereof;

FIG. 7 is a perspective view of a modified embodiment of
the design shown in FIGS. 1-6;

FIG. 8 is a front elevational view thereof;

FIG. 9 is a rear elevational view thereof;

FIG. 10 is a left side elevational view thereof, the side
opposite being a mirror image;

FIG. 11 is a top plan view thereof; and

FIG. 12 is a bottom plan view thereof.
